Primary Examiner — Prabhakar Deshmukh(74) *Attorney, Agent, or Firm* — Seyfarth Shaw LLP(57) **CLAIM**

The ornamental design for a latch, as shown and described.

DESCRIPTIONFIG. 1 is a perspective view of a latch showing my new design;
FIG. 2 is a top plan view thereof;

FIG. 3 is a bottom plan view thereof;

FIG. 4 is left side elevational view thereof;

FIG. 5 is right side elevational view thereof;

FIG. 6 is a front elevational view thereof; and,

FIG. 7 is a rear elevational view thereof.

The broken line showing is for environmental purposes only and forms no part of the claimed design.
